US00D429453S

United States Patent

[19]

Imboden et al.

[11] Patent Number: Des. 429,453

[45] Date of Patent: ** Aug. 15, 2000

[54] STAPLER

[75] Inventors: **Ethan F. Imboden; Federico Carandini; Eric Chan**, all of New York, N.Y.

[73] Assignee: **Hunt Holdings, Inc.**, Wilmington, Del.

[**] Term: **14 Years**

[21] Appl. No.: **29/101,172**

[22] Filed: **Feb. 26, 1999**

[51] LOC (7) Cl. **19-02**

[52] U.S. Cl. **D8/50**

[58] Field of Search **D8/49, 50, 61; D19/65, 72; 227/120, 127, 128, 132, 134, 156**

[57] CLAIM

The ornamental design for the stapler, as shown and described.

DESCRIPTION

FIG. 1 is a perspective view of a first embodiment of our design for a stapler;

FIG. 2 is a front elevational view of the stapler shown in FIG. 1;

FIG. 3 is a top end view of the stapler shown in FIG. 1;

FIG. 4 is a left side elevational view of the stapler showing the opposite side of the stapler depicted in FIG. 1;

FIG. 5 is a rear elevational view of the stapler shown in FIG. 1;

FIG. 6 is a bottom end view of the stapler shown in FIG. 1;

FIG. 7 is a perspective view of a second embodiment of our design for a stapler;

FIG. 8 is a front elevational view of the stapler shown in FIG. 7;

FIG. 9 is a top end view of the stapler shown in FIG. 7;

FIG. 10 is a left side elevational view of the stapler showing the opposite side of the stapler depicted in FIG. 7;

FIG. 11 is a rear elevational view of the stapler shown in FIG. 7;

FIG. 12 is a bottom end view of the stapler shown in FIG. 7;

FIG. 13 is a perspective view of a third embodiment of our design for a stapler;

FIG. 14 is a front elevational view of the stapler shown in FIG. 13;

FIG. 15 is a top end view of the stapler shown in FIG. 13;

FIG. 16 is a left side elevational view of the stapler showing the opposite side of the stapler depicted in FIG. 13;

FIG. 17 is a rear elevational view of the stapler shown in FIG. 13; and,

FIG. 18 is a bottom end view of the stapler shown in FIG. 13.

The broken lines in each respective embodiment are shown for illustrative purposes only and form no part of the claimed design.
